UNITED STATES PATENT OFFICE.

AARON SAWYER NICHOLS, OF NEW YORK, N. Y.

LUMBER-DRYING APPARATUS.

1,140,762.

Specification of Letters Patent. Patented May 25, 1915.

Application filed February 5, 1914. Serial No. 816,673.

To all whom it may concern:

Be it known that I, AARON S. NICHOLS, a citizen of the United States, residing in New York, in the county of New York and State 5 of New York, have invented a new and useful Improvement in Lumber-Drying Apparatus, of which the following is a specification.

This invention relates to improvements in 10 lumber drying apparatus.

The object of the invention is to provide a drying apparatus for lumber so arranged that the ventilation of the drying room or 15 rooms may be positively controlled and regulated and more particularly to provide an arrangement whereby all the air ventilating outlets discharge the outgoing air into a single stack or flue, thus insuring an outward uniform flow of air through the 20 ventilating outlets.

The invention furthermore consists in the improvements in the parts and devices and in the novel combinations of the parts and devices herein shown, described or claimed.

Hitherto, it has been the general practice 25 to provide each ventilating outlet of a lumber drier with a separate and independent stack or flue to conduct the air to the atmosphere and it has always been assumed that 30 the air from the drying room or rooms is drawn or sucked out through all of such ventilating outlets and stacks. However, by a series of experiments extending over a considerable period of time I have determined

35 that not only do some of the ventilating outlets and flues fail to have a partial vacuum created therein and draw air outwardly therethrough but in some of such outlets and flues the pressure is increased and air is actually

40 forced therethrough into the drying room or rooms. In other words, while some of the ventilating outlets and separate flues are performing their function in some parts of the drying room, others fail to perform 45 their proper function with the result that the ventilation cannot be controlled and some parts of the lumber are dried more than other parts and at varying rates.

I have discovered and herein my invention 50 consists that by conducting the air from all the ventilating outlets to a single stack or flue, that the difficulties and disadvantages hereinbefore mentioned may be overcome and the ventilation of the drying room or 55 rooms absolutely controlled. Other advantages result from this new arrangement,

among which may be mentioned cheaper cost of installation inasmuch as a single flue is made to take the place of the large number of flues hitherto thought necessary which, in 60 cases where the flue or flues must be extended to a relatively great height to secure the proper draft, greatly decreases the cost.

In the drawing forming a part of this specification, I have shown one arrangement 65 of drying apparatus embodying my improvements and in said drawing, Figure 1 is a top plan view of a drier showing my improvements in connection therewith, the stack or flue being shown in section. Fig. 70 2 is a vertical section taken on the line 2-2 of Fig. 1. Fig. 3 is a similar section but at right angles thereto taken on the line 3-3 of Fig. 1. Fig. 4 is a view similar to Fig. 2 showing a slightly different arrangement 75 of the pipes forming communication with the stack.

In said drawing, the building is shown as constructed of concrete or other suitable material and is provided with two drying rooms 80 A A and an inclined roof B. It will, however, be manifest that any number of drying rooms may be provided in a single building. The front and rear walls of each room are provided with doors 10, 10 through which 85 the lumber may be taken in and out of the rooms. Said walls are also provided with a plurality of air inlets, the same comprising openings 11 on the outer sides of the walls and about half-way up thereon, and inlet 90 openings 12 on the inner sides of the walls near the ceiling, said openings being connected by a vertically extending flue 13. In the side walls of the drying rooms are located a plurality of ventilating outlets 14, 95 14, the same comprising openings located near the floor line of the room and which communicate with or lead into vertically arranged flues 15 constructed in the walls. As shown most clearly in Figs. 1 and 3, the 100 ventilating outlets in the partition or wall 16 between the two rooms are alternately arranged, two outlets leading from one room and two from the other. Each set of flues 15 in each wall communicate with a hood 105 17, see Fig. 3, there being three of said hoods extending parallelly with the walls of the room and located over the tops of the flues 15. The inner hood 17 communicates directly with a large flue or stack 18 which is adapted 110 to carry off all the air to the atmosphere and is of such height as to create the proper

draft, said flue or stack having on its upper end a cupola 19. The outside hoods 17 communicate with said flue or stack 18 by means of pipes 20, 20, the same tapping into the stack 18 at a considerable height above the center hood 17 as shown in full lines Fig. 2, this arrangement being necessary where a room or space is needed above the drying rooms in the building. When no such rooms or space are required above the drying rooms, the connecting pipes from the outside hoods 17 to the stack 18 may be located as indicated at 21 in Fig. 4.

When thick stock is being dried, only slight movement of air is necessary, whereas when thin stock is being dried, a rapid movement of the air is desired and to provide for this regulation of air, I use dampers 22, 22 slidably mounted over the ventilating outlets 14, said dampers being adjustable by means of hand-operating rods 23.

With the arrangement of the ventilating outlets which I have shown and described, I have found that the efficiency of the drier is much greater than driers hitherto commonly used and in which separate flues or stacks are provided for each of the ventilating outlets and this increased efficiency is procured with an arrangement which is cheaper than those hitherto used, and furthermore the ventilation may be accurately controlled.

Although I have herein shown and described what I now consider the preferred embodiment of my improvements, yet it will be understood that various changes and modifications may be made without departing from the spirit of the invention, and all such changes and modifications are contemplated as come within the scope of the claims appended hereto.

I claim:

1. A lumber drying apparatus comprising a drying room having an air inlet ventilating means, a plurality of air ventilating outlets at the sides of said room and at a substantial distance beneath the tops of said sides, flues extending upwardly of the walls thereof, a stack, a conduit communicating

with all of said outlets and to said stack 50 whereby to prevent any of said outlets acting as air inlets.

2. A lumber drying apparatus comprising a drying room provided with an air inlet ventilating means, a plurality of air 55 ventilating outlets located at the side of a room and spaced well below the ceiling, and a stack connected to all of said outlets by independent flues extending upwardly of the walls of said room.

3. A lumber drying apparatus comprising a drying room having an air inlet ventilating means and a plurality of air 65 ventilating outlets near the floor thereof, flues extending upwardly of the walls thereof, 65 a hood into which said flues open and discharge the air, a stack, a passageway from said flue to said stack whereby to prevent any of said outlets acting as air inlets, and means for controlling the outlets individually.

4. A lumber drying apparatus comprising a drying room having an air inlet ventilating means and a plurality of air 75 ventilating outlets near the floor thereof, flues extending upwardly of the walls thereof, a hood into which said flues open and discharge the air, a stack, a passageway from said flue to said stack whereby to prevent any of said outlets acting as air inlets, and 80 means for controlling the outlets individually and collectively.

5. A lumber drying apparatus comprising a plurality of drying rooms each having air inlets and a plurality of air 85 ventilating outlets near the bottom of the vertical walls thereof, a stack, hoods at the top of said vertical walls with which said outlets communicate, a passageway from each hood to said stack, each of said hoods serving to prevent any of the outlets connected to it from acting as inlets.

Signed this 13 day of January, 1914, in the presence of two witnesses.

AARON SAWYER NICHOLS.
